HIS ATTORNEY.

UNITED STATES PATENT OFFICE.

HUGO LENTZ, OF BERLIN, GERMANY.

REVERSING-BRAKE FOR TURBINE-ENGINES.

No. 811,856.

Specification of Letters Patent.

Patented Feb. 6, 1906.

Application filed June 26, 1905. Serial No. 267,068.

To all whom it may concern:

Be it known that I, HUGO LENTZ, a subject of the German Emperor, residing at Berlin, Germany, have invented a new and useful 5 Reversing-Brake for Turbine-Engines; and I do hereby declare the following to be a full, clear, and exact description of the same.

The object of this invention is to provide an elastic or yielding means for braking a rotary shaft and for assisting in the reversal thereof.

The form or embodiment illustrated in the accompanying drawings is especially applicable to braking the driving-shaft of a turbine-engine driven either by jets of steam or by pressure due to explosions of gas. The form of braking or retarding means may be any suitable for this purpose; but I prefer and show in the drawings a device which 15 utilizes steam as the elastic braking medium and which comprises the casing of the turbine-engine, one or more projections carried by or moved by the turbine-wheel, and one or more projections, preferably movable, extending inward from the casing.

Referring to the accompanying drawings, Figure 1 is a vertical section through the upper half of a turbine-engine, showing one of the projections or stops carried by the turbine-wheel, and the power-shaft being shown broken away. Fig. 2 is an internal view of the turbine-engine, one half or shell being removed.

a indicates the shaft, driven by the turbine-engine.

b indicates the turbine-wheel.

c indicate the paddles or buckets, provided with impact-faces. I have shown peripheral paddles, which may be like those especially 40 described and claimed in my companion application, Serial No. 253,112, filed March 31, 1905, and which are so formed as to permit the driving of the wheel in either direction. The wheel is also provided with a continuous 45 ring at the extremities of the paddles or buckets and with outwardly-extending projections *d* from such ring. In the illustration I have shown two such projections. The projections, driven in unison with the wheel, 50 move freely in an annular chamber *g* in the turbine-casing and having three of its walls, the sides, and the outer peripheral wall formed by recesses or hollows in the two shells or halves *e* of the turbine-casing, and

55 the fourth or inner peripheral wall of such annular chamber being the rim of the ring.

Through one side of the turbine-casing a plate or wing *f* is projected, so as to have its forward edge in contact with or near to the rim of the ring. Such plate or wing is slidably fitted in the casing and may be normally in the advanced position shown and there yieldingly held by a spring, air-cushion, or other device, or may be normally out of the path of movement of the projection *d* and advanced, when desired, to the illustrated position by mechanical connections when braking is to be accomplished. When advanced to the position shown, the wing or plate *f* completely closes annular chamber *g*.

As seen in Fig. 2, the wing or slide *f* may be constantly pressed forward by a coiled spring *n* at the rear of the wing and housed within a cap or small casing *m*. The wing *f* has a flat-face, and the projections *d* of the running-wheel are also provided with inclined faces. It will be obvious that as the wheel *b* revolves in either direction the passing projections *d* will repeatedly push back the wing *f*, and such wing will be as repeatedly thrust forward by the spring *n*.

Above and below the wing or slide *f* are ports *h* for admission of elastic medium, such as water or steam, to the annular chamber *g*. I prefer, however, to use steam for this purpose and to connect the illustrated ports with the same supply-pipes which deliver steam for driving the turbine-wheel. If desired, the devices for controlling the supply of the steam through ports *h* and for moving the plate or wing *f* to the advanced position may be interconnected, so as to require but a single handle for first advancing the wing or locking it in advanced position and then supplying the steam to either the upper or lower port. I may also combine the connections for supplying steam to the nozzle of the turbine with those for supplying steam through either of the ports *h* in such a manner as to positively assure the cutting off of the first-mentioned supply before the admission of the second-mentioned supply. It is, however, not absolutely necessary to employ any manual means for moving the wing or plate *f*. If normally held in the advanced position by a spring which exerts but a light pressure, the plate or wing *f* will be thrown from the path of the rapidly-moving projections *d*, the contacting parts of the wing and projections being preferably rounded for this purpose.

The operation of the illustrated device is as follows: Assuming that the turbine-wheel

- has been running at a high speed in the direction of the arrow *k* and it is desired to brake such wheel and to reverse it, in such event the supply of steam through the nozzle is cut off and steam is admitted through the upper port *h*, and the moving upper projection then tends to compress such steam between itself and the wing *f*, which is in the advanced position. The power exerted by the rotating wheel is therefore resisted by the steam, which opposes an elastic or yielding resistance, and the continual supply of steam to the chamber *g* finally results in a complete stopping of the wheel, and then if continued long enough imparts a tendency to movement thereof in the opposite direction. Thereafter the supply of steam to the buckets or paddles *c* may be continued, so as to drive the wheel in either direction. When the turbine-wheel is running in a direction the reverse of that indicated by the arrow *k*, braking of the wheel will be effected as a result of admitting steam through the port below the wing or plate *f*.
- What I claim, and desire to secure by Letters Patent, is—
1. In combination, a turbine-wheel, a casing therefor provided with an annular chamber, a projection on the wheel and moving through said chamber, and means for interposing elastic resisting medium in the chamber to the travel of the projection.
  2. In combination, a turbine-wheel, a casing therefor, an annular chamber between said parts, a projection carried by said wheel, and means for interposing elastic resisting medium in the chamber to the travel of the projection. 35
  3. In combination, a turbine-wheel, a casing therefor, an annular chamber between said parts, a projection carried by said wheel, and means for supplying steam to said chamber to interpose a yielding resistance to the travel of the projection. 40
  4. In combination, a turbine-wheel, a casing therefor, an annular chamber between said parts, a projection carried by said wheel and moving through the chamber, a movable projection carried by the casing and entering the chamber, and means for interposing elastic resisting medium between the two projections. 45
  5. In a reversing-brake device for turbines, a rotary piston, a projection driven by said piston, and means for interposing elastic resistance medium in the path of said projection. 50

In testimony whereof I have signed my name to this specification in the presence of two subscribing witnesses.

HUGO LENTZ.
